UNITED STATES PATENT OFFICE.

FREDERICK SOHON, OF WASHINGTON, DISTRICT OF COLUMBIA.

CARBURETER-VALVE.

1,161,742.

Specification of Letters Patent. Patented Nov. 23, 1915.

Application filed March 13, 1915. Serial No. 14,161.

To all whom it may concern:

Be it known that I, FREDERICK SOHON, a citizen of the United States, residing at Washington, in the District of Columbia, have invented certain new and useful Improvements in Carbureter Valves; and I do declare the following to be a full, clear, and exact description of the invention, such as will enable others skilled in the art to which it appertains to make, and use the same, reference being had to the accompanying drawings, and to the letters and figures of reference marked thereon, which form a part of this specification.

This invention relates to valves with particular reference to carbureter valves for internal combustion engines, and the invention has for its object to provide an air valve for carbureters and the like in which the usual tension spring is eliminated, so that the valve when once properly adjusted will thereafter remain in its proper efficient operative position.

A further object of the invention is to provide a novel construction for priming the motor to which this valve is attached, so as to enrich the combustible mixture for facilitating the starting of the motor.

A further object of the invention is to provide a carbureter valve, which when properly set will automatically open to supply the necessary quantity of air to the carbureter at varying motor speeds, so that the character of the combustible mixture will at all times be maintained in the most efficient and economical condition.

With these objects in view the invention consists in the novel construction of the valve, and in certain combinations of parts, all of which will be first fully described and afterward specifically pointed out in the appended claims.

Referring to the accompanying drawing: Figure 1 is a vertical sectional view through the valve, and Fig. 2 is a horizontal sectional view taken on line 2--2 of Fig. 1.

Like numerals of reference indicate the same parts throughout the two figures, in which—

1 indicates the carbureter valve which it will be understood may be applied to any form of carbureter, and 2 indicates the air passage connecting the valve to its carbureter, the latter not being shown.

The valve 1 comprises a casing 3 having an enlarged chamber 4 and an upper restricted chamber 5. 6 indicates a plug or closure which is provided with a plurality of openings 7 through which air passes to the enlarged chamber 4, which chamber is in full communication with or a continuation of the air passage 2, as will be clearly seen from Fig. 1. Extending vertically through and centrally of the casing 3 is a tubular member 8, 65 shouldered at 9 and threaded into the plug or closure 6 at 10, the upper end of said tubular member 8 being threaded to receive a nut 11 in the manner as shown, said tubular member 8 being provided centrally thereof with a transversely elongated port 12, a relatively small port 13 above said central port and an enlarged lower port 14. Centrally disposed within the tubular member 8 and rotatable therein is a tubular core 15, said core 15 being provided with an enlarged port 18 for communication with the port 13 in the tubular member 8, and provided centrally thereof with a port 19 (Fig. 2) communicating with the central port 12 80 so as to enrich the combustible mixture in the tubular member 8, said tubular core 15 being provided with a head 20 for manual rotation of the same.

16 indicates a lower tubular core disposed and rotatable within the lower portion of the tubular member 8, said lower tubular core 16 being provided with a vertical passage 21 and an operating lever 17 for rotating the said lower tubular core 16. As will appear from Fig. 1 the said lower

tubular core 16 is provided with an upwardly extending wall 22 behind and commanding the lower port 14 in the tubular member 8.

Threaded in the tubular core 15 is a headed screw 23 of sufficient length to cover the upper port 18 in the said tubular core 15 when said headed screw has reached the limit of its inward movement, said headed screw being capable of rotation manually as

will be apparent from Fig. 1.

Mounted on the tubular member 8 and freely slideable thereon is the valve member 24, the same being preferably provided with a lower flange 25 for effectually closing the chamber 26 in the plug or closure 6 in the manner as shown in Fig. 1, while said valve member 24 is also preferably provided with

an upper flange 27 extending within the upper reduced chamber 5 in the casing, an annular space 28 being provided between the upper flange 27 and the surrounding vertical wall of the upper reduced chamber 5. The slidable valve member 24 is provided therein with a chamber 29 terminating at a point below the upper flange 27, the top surface of the valve member 24 being provided with a vertical port 30 which is at all times in communication with the chamber 29 within the valve member 24 and with the upper chamber 5 within the valve casing.

15 Referring again to the upper tubular core 15 and particularly to Fig. 2 it will be seen that said tubular core 15 is provided with what I term a shutter 31 suitably secured to the upper tubular core 15, and lying within 20 the central port 12 in the tubular member 8.

Having thus described the several parts of this invention its operation is as follows: The valve being applied to a carbureter and the passage 2 supplying the carbureter with air, air passing to the carbureter must be drawn through said passage in the following manner. As soon as there is a draw or suction on the carbureter a rarefaction is produced in the upper chamber 5 in the casing 30 above the valve member 24. If this rarefaction or reduction of pressure be slight it will be accounted for and balanced by atmospheric air passing through the ports 13 and 18 in the tubular member 8 and tubular core 15 respectively, which are both in communication with the air passage 21 in the lower tubular core 16. When however, the reduction of pressure in the chamber 5 is of such an extent that the same cannot be balanced by ingress of air therein passing through the small port 13, as just stated, which balance is of course aided by the weight of the valve member 24, said reduction of pressure or partial vacuum within the chamber 28 raises the valve 24 in the direction of the dotted lines indicated in Fig. 1 thus lifting the flange 25 of the valve 24 and allowing air to pass through the openings 7 in the plug 6 to the air passage 2, the quantity of air so passing to the air passage 2 depending upon the extent of lift of the valve member 24 as will be of course perfectly understood. At slow motor speeds which normally require an enriched combustible mixture the partial vacuum produced within the chamber 5 will be relatively low accomplishing little or no movement or lift of the valve member 24, and consequently the supply of atmospheric air to the motor at low motor speeds is relatively small. As the motor speed is increased a higher partial vacuum is produced in the upper chamber 5 which causes the valve member 24 to be raised in proportion of course to the extent of partial vacuum created and sustained in

the upper chamber 5, thus allowing air to pass through the openings 7 into the passage 2. It will thus be seen that the lift of the valve member 24 and the quantity of air passing into the air passage 2 will depend upon the amount of suction or draft on the carbureter which in turn is governed by the speed of the motor. In order to properly and accurately adjust the valve so as to admit the proper quantity of air at high and low motor speeds the headed screw 23 is provided, so as to partially close or open the enlarged port 18 in the tubular core 15 so that the quantity of air passing into the upper chamber 5 through the air passage 21 can be delicately adjusted so as to cause a movement or not of the valve member 24 upon a very slight suction or draft on the carbureter as it is of course apparent that the extent of partial vacuum within the upper chamber 5 depends upon the extent of its opening to the atmosphere at a given engine speed. As the valve 24 rises to accommodate the partial vacuum within the upper chamber 5 said valve uncovers the central ports 12 and 19 in the tubular member 8 and tubular core 15 respectively, which allows atmospheric air to pass into the chamber 29 within the valve member 24 and through the port 30 into the upper chamber 5 to relieve the partial vacuum in said upper chamber to limit the lift of the said valve member. In order to regulate the quantity of air passing through the said ports 12 and 19 into the valve member the shutter 31 hereinbefore mentioned is provided, which by means of rotation of the tubular member 15 can be positioned to close or open either wholly or partially communication with the air passage 21. By means of this construction the extent of lift of the valve member 24 at a given draft or suction on the carbureter can be delicately adjusted.

As it is important for ready starting of internal combustion motors to greatly enrich the combustible mixture passing to the motor which is termed "priming" I provide the lower port 14 in the tubular member 8 which is commanded by the lower tubular core 16, so that when it is desired to greatly enrich the mixture for starting, the lower tubular core 16 is rotated by the lever 17 to open communication between the chamber 29 within the valve member 24 and the air passage 21, so that no appreciable reduction of pressure can be maintained within the upper chamber 5 to raise the valve member 24, and consequently a very limited and restricted quantity of air is allowed to pass to the carbureter when the said port 14 in the tubular member 8 is opened or uncovered by the wall 22 of the lower tubular core 16.

Having thus fully described the invention, what I claim as new and desire to se-

cure by Letters Patent of the United States
is—

1. A valve including a casing having an air passage leading therefrom, and a chamber in communication with said air passage, said casing being also provided with a second chamber in communication with said air passage, a tubular member disposed vertically through said chambers and provided with a central port and with a port above said central port and with a port below said central port, a tubular core rotatable within said tubular member and provided with ports in alinement with the said central port and with the said port above said central port in the said tubular member, means within said tubular core commanding the uppermost port therein, a lower tubular core provided with an air passage open to the atmosphere, and including means for commanding the lowermost port in the said tubular member, the said casing being provided with an air port opening to the atmosphere, a valve member freely slideable on said tubular member for closing said air port in the casing opening to the atmosphere, said valve member being provided with a chamber in communication with the lowermost port in the said tubular member and adapted to open and close the said central port in the said tubular member, the said valve member being provided with a port communicating with the said chamber within the said valve member, and with the said second chamber in the said casing, the said valve member extending within the said second chamber in the said casing and providing an annular space between the said valve member and the walls of the said second chamber in the said casing, substantially as described and for the purposes set forth.

2. A valve including a casing and provided with an air passage leading therefrom and with a chamber in communication with said air passage, and with a second chamber in communication with said air passage, a tubular member disposed within said chambers and open to the atmosphere at one end, said tubular member being provided with two ports one of which is in communication with the said second chamber in the said casing, a tubular core movable within said tubular member and provided with ports in alinement with the said ports in the said tubular member, the said casing being provided with a port opening to the atmosphere, a valve member mounted on said tubular member and freely slideable thereon to command the said port in the said casing open to the atmosphere, the said valve member being provided with a chamber and including means for commanding the lowermost port in said tubular member, said valve member being provided with a port communicating with the said cham-

ber within the said valve member and with the said second chamber in the said casing, the said valve member extending upwardly within the said second chamber to provide an annular space between the said valve member and the walls of the said second chamber, substantially as described and for the purposes set forth.

3. A valve including a casing and provided with an air passage leading therefrom and provided with a chamber in communication with said air passage and provided with a port opening to the atmosphere entering said chamber and provided with a second chamber in communication with said air passage, a tubular member within said chambers, said tubular member being provided with an air passage open to the atmosphere and provided with a port communicating with said second chamber in the casing and said air passage in the said tubular member, said tubular member being also provided with a second port in communication with said air passage therein, a valve member mounted and freely slideable on said tubular member and provided with a chamber, said valve member commanding said second port in said tubular member to open and close communication between the chamber in said valve member and the air passage within said tubular member, said valve member being provided with a port in communication with the chamber in said valve member and with the said second chamber in said casing to provide communication between the said chamber in the valve member and the air passage in the said tubular member by way of the said second chamber in the said casing, the said valve member commanding the said port in the said casing open to the atmosphere and extending within the said second chamber in the said casing to provide an annular space between the said valve member and the wall of the said second chamber in the said casing, and means for independently opening and closing communication between the air passage in the said tubular member and the said ports therein, substantially as described and for the purposes set forth.

4. A valve including a casing provided with an air passage leading therefrom and provided with a chamber in communication with said air passage and provided with a second chamber in communication with said air passage, and provided with a port opening to the atmosphere, a tubular member within said chambers provided with an air passage open to the atmosphere, a valve member freely slideable on said tubular member and provided with a chamber, means for effecting communication between the said chamber in the said valve member and the said air passage in the said tubular member, means for effecting communication

between the said second chamber in the said casing and the said air passage in the said tubular member, means for effecting communication between the said chamber in the 5 said valve member and the said second chamber in the said casing, said valve commanding the said port in the said casing opening to the atmosphere and extending to the said second chamber in the said casing 10 to provide communication between the said second chamber in the said casing and the air passage leading therefrom, and means for independently opening and closing communication between the air passage in the 15 said tubular member with the said chamber in the valve member and with the said second chamber, substantially as described.

5. A valve including a casing the same being provided with an air passage leading 20 therefrom and provided with a chamber in communication with said air passage and provided with a second chamber in communication with said air passage and provided with a port opening to the atmosphere, a valve member slidably mounted in 25 said first mentioned chamber for commanding the said port open to the atmosphere, said valve member providing a space between the same and the wall of the said 30 second chamber in the casing, means for effecting a relatively slight communication between the said second chamber in the casing and the atmosphere at a point above the said valve member, means for effecting communication 35 between the said second chamber in the said casing and the atmosphere through the said valve member and means for independently controlling the extent of the said communication between the second 40 chamber in the casing and the atmosphere and between the said second chamber in the said casing and the atmosphere through the said valve, substantially as described and for the purposes set forth.

45 6. A valve including a casing having a chambered interior and having an air passage communicating with the said chambered interior and leading from the said casing, the said chambered interior communicating with the atmosphere by means of a port 50 opening thereto, a slidale valve member within the said chambered interior, means for sustaining a partial vacuum within said chambered interior at a point above the said 55 valve member to lift the same, means for establishing communication between said chambered interior above the said valve member and the atmosphere commanded by the said valve member to regulate the extent of partial vacuum in the said chambered interior above the said valve member, and further means for establishing com-

munication between the said chambered interior and the atmosphere independent of 65 said first mentioned means for establishing communication between the said chambered interior above the said valve member with the atmosphere and means for regulating the extent of these two last communications with the atmosphere, substantially as described. 70

7. A valve including a casing and having a chambered interior, an air passage in communication therewith and leading from the casing and a port opening to the atmosphere, 75 a slidale valve member disposed in said chambered interior and commanding said port open to the atmosphere, means for sustaining a partial vacuum in said chambered interior above said valve member to lift the 80 same, means for regulating the extent of partial vacuum within said chambered interior above said valve member, and further means for regulating the extent of partial vacuum within the chambered interior 85 controllable by the movement of the said valve, and further means for controlling the extent of partial vacuum in the said chambered interior above the said valve member to regulate the lift thereof. 90

8. A valve including a casing having a chambered interior, an air passage in communication therewith and a port opening to the atmosphere, a slidale valve member within said chambered interior and commanding said port opening to the atmosphere, means for sustaining a partial vacuum in said chambered interior above the said valve member to lift the said valve member, independent means for regulating the extent of partial vacuum within the chambered interior above the said valve member and manually operable means for regulating the extent of vacuum in the said chambered interior above the valve member 100 to regulate the lift of said valve member. 105

9. A valve including a casing having a chambered interior, an air passage leading therefrom and a port opening to the atmosphere, a slidale valve member within the 110 chambered interior, means for sustaining a partial vacuum within said chambered interior above the said valve member to lift the said valve member and means for controlling the extent of partial vacuum in the 115 said chambered interior above the said valve member to control the lift thereof.

In testimony whereof, I affix my signature, in presence of two witnesses.

FREDERICK SOHON.
